Application July 12, 1934, Serial No. 734,747

9 Claims. (Cl. 179—26)

The present invention relates to telephone systems in general, but is concerned more particularly with semi-automatic telephone systems whereby connections between manual lines entering an exchange may be set up by automatic switches under the control of an operator at a switchboard in a remote exchange.

In system of this type connections are set up between manual magneto lines by automatic switching apparatus responsive to control exercised over a control trunk extending between the manual magneto exchange and a remote operating center and was designed to improve service in rural communities by making it possible for a remote operator, instead of a local operator, to control the connections. The remote operator can give practically the same service to the local subscribers as could the local operator and can give the service in very much the same manner, the chief difference being that she operates a dial instead of plugging up cords. This equipment is intended to replace manual magneto switchboards which cannot profitably carry the cost of a local operator. Systems of the foregoing type are commonly known as remotely controlled exchanges and generally referred to as R. C. X.'s.

The main object of the present invention is the provision of a distributor circuit for operating two remotely controlled exchanges, or R. C. X.'s, over a single control trunk extending to a remote operating center.

One feature of the invention relates to the means whereby the control trunk is made busy during the establishment of a connection in one of the R. C. X.'s to prevent a call from the other R. C. X. from interfering therewith.

Another feature of the invention relates to the means whereby calls waiting in both R. C. X.'s alternately take the control trunk into use.

Other features of the invention will be apparent from the following description of the accompanying drawings comprising Figs. 1 and 2.

Referring now to Fig. 1: the upper left-hand corner diagrammatically represents one of the R. C. X.'s, or R. C. X. #1 and the lower left-hand corner diagrammatically represents the other R. C. X. or R. C. X. #2. The detail circuits of R. C. X. #1 and R. C. X. #2 are fully disclosed and described in a copending application, S. N. 676,439, filed June 19, 1933. The reference characters in the instant application correspond to the reference characters shown in Fig. 5 of such copending application. R. C. X. #1 is connected to the distributor circuit by way of conductors

451 and 452, while R. C. X. #2 is connected by way of the dotted conductors 451' and 452'.

The right-hand portion of Fig. 1 and the left-hand portion of Fig. 2 show the relays and circuits of the distributor circuit which extends by way of conductors 453 and 454 to the remote operating center shown at the right of Fig. 2.

Switch S in Fig. 1 indicates a so-called minor switch having a rotary magnet, Rot. Mag., for stepping wiper 90 one step upon each energization, and a release magnet, Rls. Mag., for restoring the wiper to its normal position. Off normal springs ON are normally open when wiper 90 is in normal position and close when the wiper moves off normal.

The equipment located at the remote operating center comprises the usual operator's head set, drop, calling device C. D., repeating coil RC2, and the ringing, monitoring and connecting keys. This equipment is identical to that shown in Fig. 5 in the copending application. By a comparison between the copending and instant applications it can readily be seen that the distributor circuit is inserted in the control trunk between the remote operating center and the two R. C. X.'s, such distributor circuit being preferably located at the R. C. X. closest to the operating center.

The general operation is as follows: A local subscriber in one of the R. C. X.'s, upon initiating a call by turning his hand generator, causes a finder in such local exchange to find his line and operate certain relays in the distributor circuit, if idle, to signal the remote operators over the control trunk extending to the remote operating center. The remote operator answers the call, dials back over the same control trunk and distributor branch to operate automatic switches in the local calling R. C. X. to establish the desired local connection between the local calling and local called lines. After ringing the called party the remote operator then retires from the local connection and the distributor circuit and control trunk is then made available for other calls from both R. C. X.'s. Either the local calling or called line can release the local connection by turning the hand generator.

Having given a general description of the system and drawings, a detailed description of the circuit operations will now be given.

For this purpose it will be assumed that one of the regular magneto subscribers served by R. C. X. #1 wishes to be connected with another local subscriber whose line also terminates in the same R. C. X. The calling subscriber operates

his hand generator in the usual manner, projecting ringing current over his line to operate and lock the line relay at the exchange. In response to the operation of the line relay a finder in the local exchange hunts for and finds the calling line. In response to the finder finding the calling line ground is momentarily connected to a slow-to-release relay 430. The foregoing detail circuit operations up this point are described in detail in the aforesaid copending application.

Relay 430 is momentarily operated and at armatures 432 and 481 completes a circuit for energizing relay 20 as follows: from ground by way of working contact and armature 432, conductor 451, armature 42 and resting contact, lower winding of relay 20, conductor 452, armature 481 and working contact, and through the resistance to grounded battery. At armature 21 relay 20 temporarily completes a locking circuit for itself by way of armature 41 and resting contact through its upper winding and at armature 22 completes a circuit for energizing relay 40 in case the distributor circuit and control trunk is not in use. The circuit for relay 40 extends from grounded armature 22, armatures 35 and 61 and through the lower winding of relay 40 to grounded battery. At armature 41 relay 40 opens the locking circuit of relay 20 and grounds conductor 91 to complete the energizing circuit for slow to energize relay 150. At the resting contact of armature 42 relay 40 opens a point in the original energizing circuit of relay 20 and at the working contacts of armatures 42 and 43 prepares points in the talking circuit between R. C. X. #1 and the control trunk. At armature 44 relay 40 completes a locking circuit for itself as follows: from ground by way of armatures 63, 34, and 44 through its upper winding to grounded battery. Armature 44 also connects this same ground to the second or #2 contact accessible to wiper 90 of which S. At armature 45 relay 40 opens a point in the energizing circuit of relay 30 to prevent its energization in case relay 10 is energized on a call from R. C. X. #2. At armature 46 relay 40 opens a point in the locking circuit of relay 30 and at armature 47 completes an energizing circuit for slow to operate relay 160 as follows: from grounded armature 73 and resting contact, armatures 64 and 47, conductor 99, normally closed springs controlled by armature 141 and through the winding of relay 160 to battery.

Relay 20 deenergizes in response to the operation of relay 40 and at armature 22 opens a point in the original energizing circuit of relay 40 which, however, is locked energized. Relay 160, upon energizing over the above traced circuit, at armatures 161 and 162 and their working contacts connects ground and battery to conductors 454 and 453 to operate the drop at the remote operating center and at armature 163 completes an obvious circuit for energizing slow to operate relay 140. The circuit for operating the drop at the remote operating center may be traced as follows: from ground by way of working contact of armature 161 and said armature, control trunk conductor 454, upper left-hand winding of repeating coil RC2, spring 461, and resting contact of key K, winding of drop, lower left-hand winding of repeating coil RC2, control trunk conductor 453, armature 162 and working contact, and through the resistance to grounded battery.

Relay 150, upon energizing, at the resting contacts of armatures 151 and 152 disconnects relay 130 from the control trunk conductors and at 75 their working contacts prepares a point in the

talking circuit. At armature 153 relay 150 opens a point in the impulsing circuit to relay 120 and rotary magnet Rot. Mag. After an interval slow to operate relay 140 energizes and at armature 141 completes a locking circuit for itself from grounded conductor 99 as well as opening the circuit to relay 160 and the normally closed springs controlled by armature 141.

Relay 160, upon deenergizing, at armature 163 opens the original energizing circuit of relay 140' 10 and at armatures 161 and 162 disconnects ground and battery from the control trunk and connects the control trunk conductors 454 and 453 to conductors 92 and 93.

When the operator at the remote operating center observes the operation of the drop at her position indicating a call, she will operate the key K which at springs 460 and 464 connects her head set to the right-hand windings of repeating coil RC2 to complete the talking circuit to the calling subscriber. The talking circuit to the calling subscriber may be traced as follows: from the calling subscriber's line to conductors 268 and 269, winding of repeating coil RC1, resting contacts of armatures 432 and 481 and said armatures, conductors 451 and 452, armatures 42 and 43 and their working contacts, through the condensers C1 and C2, conductors 92 and 93, working contacts and armatures 151 and 152, resting contacts and armatures 161 and 162, and control trunk conductors 454 and 453 to the left-hand windings of repeating coil RC2. At spring 461 and its resting contact the circuit for operating the drop is opened and at the make springs on springs 461, 462 and 463 ground through the impulse springs 35 of the calling device CD is connected to both trunk conductors 454 and 453 through the left-hand windings of repeating coil RC2. A circuit may now be traced for energizing relay 80 and the line relay 302 in the common equipment of the copending application as follows: from ground the impulse springs of the calling device CD, springs 463, normally closed springs of the negative ring key, working contacts and spring 461, upper left-hand winding of repeating coil RC2, conductor 454, armature 161 and resting contact, armature 151 and working contact, conductor 92, winding of relay 80, working contact and armature 42, conductor 451, armature 432 and resting contact, upper right-hand winding of repeating coil RC1, conductor 270 and through the winding of the line relay in the common equipment to grounded battery. At the same time another circuit may be traced for energizing relay 50 in series with relays 303 and 304 shown in the common equipment in the copending application as follows: from ground through the impulse springs of the calling device CD, springs 463, springs of monitor key MK, normally closed springs of the positive ring key, springs 462, lower left-hand winding of repeating coil RC2, conductor 453, armature 162 and resting contact, armature 152 and working contact, conductor 93, winding of relay 50, armature 43, conductor 452, armature 481 and resting contact, lower right-hand winding of repeating coil RC1, conductor 271 and through the windings of relays 303 and 304 in R. C. X. #1 to grounded battery. A branch of this circuit extends through the winding of relay 110 to grounded battery for energizing this relay which at armature 111 grounds conductor 94 to energize relay 70.

Relays 50 and 80, upon energizing, at their armatures 51 and 81 completes an obvious circuit for energizing slow to release relay 70. At arm-

ture 71 relay 70 prepares a point in the impulsing circuit previously opened at armature 153, at armature 72 and resting contact opens a point in the release circuit to release magnet Rls. Mag. 5 and at the working contact of armature 72 completes a circuit for energizing slow to release relay 60. At the working contact of armature 73 relay 70 maintains the locking circuit of relay 40 and at the resting contact thereof disconnects 10 ground from conductor 99 to unlock relay 140, which thereupon deenergizes. Relay 60, upon energizing, at armature 61 opens a further point in the original energizing circuit of relay 40, at armature 62 opens a further point in the energizing 15 circuit of relay 30 to prevent its energization, at armature 63 disconnects one of the multiple grounds from the locking circuit of relay 40 now grounded at armature 73, and at armature 64 opens a further point in the circuit for ground- 20 ing conductor 99.

The operator now challenges the call and receives the number to be called. The operator now operates the calling device CD in accordance with the digits in the called number to operate 25 the automatic switches in R. C. X. #1 to complete the desired connection as described in the copending application. Relays 50, 80 and 110 follow the impulses but since relay 70 is a slow to release relay the same is maintained energized. 30 The operator rings the called subscriber by the operation of either her negative ring key or positive ring key and monitors the connection, if desired, as described in the copending application. The operation of either ring key will open the circuit to either relay 50 or 80 dependent upon the key operated but since one of such relays is energized relay 70 is maintained in energized position.

After the satisfactory completion of the desired 40 local connection the control operator will disconnect from the connection by restoring the answer and dial key K. In response to the restoration of key K relays 50, 80, and 100 deenergize and at armatures 51, 81 and 111 open the circuit to relay 70 which deenergizes after an interval. Relay 70, upon deenergizing, at armature 72 opens the circuit to relay 60 which deenergizes after an interval and at armature 73 opens the locking circuit of relay 40 which thereupon deenergizes. At armature 41 relay 40 opens the circuit of relay 150, at armature 42 restores the original energizing circuit of relay 20, at armatures 42 and 43 disconnects the trunk conductors 451 and 452, from conductors 92 and 93, at armature 44 opens 50 a point in its locking circuit, at armature 45 prepares a point in the energizing circuit of relay 30, at armature 46 prepares a point in the locking circuit of relay 30, and at armature 47 opens a point in the circuit of relay 160. Relay 150, upon deenergizing, at armatures 151 and 152 disconnects conductors 92 and 93 from conductors 454 and 453 and connects the winding of relay 130 in place thereof. Relay 60, upon deenergizing, at armature 61 prepares the circuit for relay 40, at 55 armature 62 prepares a point in the circuit for relay 30, at armature 63 prepares a point in the locking circuits of relays 30 and 40, and at armature 64 prepares a point in the circuit for relay 160. All relays have now been restored to their 60 normal positions as shown in the drawings.

It will now be assumed that a regular magneto subscriber served by R. C. X. #2 wishes to be connected with another local subscriber whose line also terminates in this R. C. X. The calling 75 subscriber operates his hand generator in

the usual manner to initiate a call. In response to a call from R. C. X. #2 relay 430' is temporarily operated in a manner similar to that described for relay 430. At armatures 432' and 481' ground and battery are temporarily connected 5 to conductors 451' and 452' to complete an energizing circuit through the lower winding of relay 10 and armature 32. At armature 11 relay 18 temporarily completes a locking circuit for itself through its upper winding and at armature 12 10 completes a circuit for energizing relay 30 as follows: from ground by way of armatures 12, 45 and 62 through the upper winding of relay 30 to grounded battery. In case the control trunk was in use then relay 30 and possibly relay 60 15 may be operated with the result that relay 30 does not energize since the energizing circuit to relay 30 includes armatures 45 and 62. Relay 30, upon energizing, at armature 31 and resting contact opens its locking circuit, at armature 31 and 20 working contact grounds conductor 91 to energize slow to operate relay 150, at armature 32 and resting contact opens the original energizing circuit to the lower winding of relay 10 to cause said relay to deenergize, at armatures 32 and 33 and 25 their working contacts prepares points in the talking circuit over conductors 451' and 452', at armature 34 opens a point in the locking circuit of relay 40, at armature 35 opens a point in the energizing circuit of relay 40, at armature 36 completes a locking circuit through its lower winding by way of armatures 46 and 63, and at armature 37 connects ground at armature 73 by way of armature 63 to conductor 99 to energize relay 160. 30 In the same manner as previously described relays 150 and 160 and then relay 140 energize to transmit a calling signal to operate the drop at the operator's position at the remote operating center.

When the operator observes the operation of 40 the drop at her position she will operate the dial and answer key K to complete a talking circuit to the calling subscriber in R. C. X. #2. This circuit may be traced as follows: from the calling subscriber's line, windings of repeating coil, resting contacts and armatures 432' and 481', conductors 451' and 452', armatures 32 and 33 and working contacts, through the condensers C1 and C2, conductors 92 and 93, and thence over the 45 previously traced circuit to the operator's head 50 set. A circuit may now be traced for energizing relay 80 in series with the line relay in the common equipment in R. C. X. #2 as follows: from ground through the impulse springs of the calling device CD, springs 463, springs of the negative 55 ring key, springs 461, upper left-hand winding of repeating coil RC2, conductor 454, armature 161 and resting contact, armature 151 and working contact, conductor 92, winding of relay 80, 60 working contact and armature 32, conductor 451', armature 432' and resting contact, upper right-hand winding of the repeating coil and through the winding of the line relay in the common equipment to grounded battery. At the same 65 time another circuit is completed for energizing relay 50 in series with other relays in the common equipment as follows: from ground through the impulse springs of calling device CD, springs 463, springs of key MK, springs of positive ring 70 key, lower left-hand winding of repeating coil RC2, conductor 453, armature 162 and resting contact, armature 152 and working contact, conductor 93, winding of relay 50, armature 33, conductor 452', armature 481' and resting contact, 75

and the lower right-hand winding of the repeating coil through the windings of the relays in the common equipment to grounded battery. A branch of this circuit extends through the winding of relay 110 to grounded battery for energizing this relay which at armature 111 grounds conductor 94 for energizing relay 70. Relays 50 and 80 at their armatures 51 and 81 also grounds conductor 94 to energize relay 70. Relay 70 and then relay 60 energize causing the deenergization of relay 140 as previously described. Relay 70 maintains relay 30 locked energized at armature 73.

The operator now challenges the call and receives the number to be called after which she operates the calling device CD in accordance therewith to operate the automatic switches in R. C. X. #2 to complete the desired connection as described in the copending application. After signalling the called subscriber and the satisfactory completion of the connection the control operator disconnects by restoring key K, whereupon relays 50, 80 and 110 and then relays 70 and 60 deenergize, as previously described. At armature 73 relay 70 opens the locking circuit of relay 30, which thereupon deenergizes. At armature 31 relay 30 opens the circuit of relay 150 which deenergizes, at armatures 32 and 33 disconnects the control trunk from conductors 451' and 452' as well as reestablishing the original energizing circuit for relay 10, at armature 34 prepares a point in the locking circuit of relay 40, and at armature 35 prepares a point in the energizing circuit of relay 40. All the relays are now restored to their normal positions and may be used on subsequent calls.

The foregoing description relates to normal operation at a time when the control trunk was not in use. It will now be assumed that a call is originated from R. C. X. #1 at the time the control trunk is in use in a call with R. C. X. #2, in which case relay 30 is energized. In response to the call relay 20 energizes and locks as before described but in this case does not complete an energizing circuit for relay 40 at armature 22 because relay 30 at armature 35 holds the circuit of relay 40 open. After the operator completes the call in R. C. X. #2 and disconnects relays 30 and 60 deenergize to complete the circuit for relay 40, whereupon the call is completed as previously described.

A similar arrangement is provided for energizing and locking relay 10 in case a call originates from R. C. S. #2 when the control trunk is in use on a call in R. C. X. #1. In this case relay 10 energizes and locks but cannot complete the circuit for relay 30 at armature 12 because relay 40 is energized. The call therefore waits until the control circuit is idle at which time the deenergization of relays 40 and 60 completes the circuit for relay 30 to allow the call to proceed as previously described. From the foregoing it can be seen that the control circuit is guarded when busy and that calls from the two R. C. X.'s alternately take the control trunk into use when calls are waiting at both R. C. X.'s.

In some instances the control operator may initiate a call either for testing purposes or for connecting to a called subscriber. In order to do this the operator actuates the key K at a time when the control trunk is idle, thereby connecting ground through the impulse springs of the calling device CD to trunk conductors 454 and 453, as previously described and this time

by way of armatures 161, 151 and 162 and their resting contacts, through the winding of relay 130 to grounded battery for energizing the same. At armature 131 relay 130 grounds conductor 94 for energizing relay 70. Relay 70 at armature 71 prepares a point in the impulsing circuit, at armature 72 and resting contact opens a point in the circuit to the release magnet Rls. Mag. of switch S, at armature 72 and working contact energizes relay 60, and at armature 73 opens a point in the energizing circuit of relay 160. At armatures 61 and 62 relay 60 opens the energizing circuits of relays 40 and 30 to prevent their energization.

The control operator now dials the digit 2 in case she desires to be connected with R. C. X. #1, or dials the digit 4 in case a connection with R. C. X. #2 is desired. Relay 130 deenergizes for each impulse and at armature 131 and resting contact completes the impulsing circuit for relay 120 and rotary magnet Rot. Mag. by way of conductor 95, armature 71, conductor 96, armature 153, conductor 97, and through the winding of relay 120 and the winding of the rotary magnet in parallel to grounded battery. Relay 70, due to its slow releasing characteristics, does not deenergize during dialling. Relay 120, upon energizing, at armature 121 disconnects ground from conductor 98 and wiper 90 of switch S. Rot. Mag. energizes once for each impulse to step wiper 90 one step for each impulse received. Off normal springs ON close on the first step of wiper 90 to prepare the circuit to the release magnet Rls. Mag.

In case the operator dialled the digit 2 then wiper 90 comes to rest in engagement with its second bank contact to prepare a circuit for relay 40. Slow to release relay 120 deenergizes shortly after the impulsing period and at armature 121 completes a circuit for energizing relay 40, as follows: from grounded armature 121, conductor 98, wiper 90, second bank contact, and through the upper winding of relay 40 to grounded battery. Relay 40, upon energizing, at armature 41 completes the circuit for energizing relay 150 and at armatures 42 and 43 connects conductors 451 and 452 to conductors 92 and 93. Relay 160 at armatures 151 and 152 disconnects relay 130 and connects conductors 454 and 453 to conductors 92 and 93, and at armature 153 opens the impulsing circuit. Relay 130 deenergizes and opens the circuit to relay 70 which, however, is maintained energized in response to the operation of relays 50, 80 and 110 as a result of the connection being completed to R. C. X. #1 by relay 150. The operation from here on is the same as previously described in the instant and copending applications. In this case, during the release of the connection relay 70 at armature 72 completes the circuit for energizing the release magnet Rls. Mag. through the off normal springs ON, thereby restoring the wiper 90 to its normal position in which position off normal spring ON opens the circuit to the release magnet.

In case the operator dialled the digit 4 instead of 2, then wiper 90 comes to rest in engagement with its fourth bank contact to prepare a circuit for relay 30. Relay 120 deenergizes after the dialling period and at armature 121 completes a circuit for energizing relay 30 as follows: from grounded armature 121, conductor 98, wiper 90, fourth bank contact, and through the lower winding of relay 30 to grounded battery. Relay 30, upon energizing, at armature 31 completes the

energizing circuit of relay 150 and at armatures 32 and 33 connects conductors 341' and 452' to conductors 92 and 93. Relay 150, upon energizing, at armatures 151 and 152 disconnects relay 130 and connects conductors 92 and 93 to conductors 454 and 453. Relay 130 deenergizes, relays 50, 80, and 110 energize, and the operation from here on is the same as previously described. During the release of the connection relay 70 closes the release circuit to Rls. Mag. to restore switch S to normal.

Having described the invention what is considered new and is desired to have protected by Letters Patent will be set forth in the following claims.

15. What is claimed is:

1. In a telephone system wherein an operator at a main exchange remote from a local exchange controls automatic switches in the local exchange over a common control trunk to complete direct connections between local subscribers' lines, a second local exchange having automatic switches controlled over said control trunk to complete direct connections between local subscribers' lines therein, two branches of said control trunk at said first local exchange, the first of said branches terminating in the first local exchange and the second branch terminating in the second local exchange, means in each branch 30 at the first local exchange operated responsive to a subscriber in either local exchange initiating a call for seizing said trunk if idle by way of its corresponding branch, and means responsive to said seizure for preventing the seizure of said trunk over the other branch and for automatically signalling the remote operator over said trunk.

2. In a telephone system, a first exchange, a second exchange, a control trunk extending from a remote operator's position and terminating in two branches, the first of said branches extending to said first exchange and the second of said branches extending to said second exchange, a first and a second relay individual to each of said branches, means for energizing the first of said relays in response to a call over the corresponding branch, means responsive thereto for energizing the second of said relays in the corresponding branch in case the control trunk is idle, and means responsive to the energization of the second relay for seizing said control trunk and for automatically signalling the remote operator thereover.

3. In a telephone system, a first exchange, a second exchange, a control trunk extending from a remote operator's position and terminating in two branches, the first of said branches extending to said first exchange and the second of said branches extending to said second exchange, a first and a second relay individual to each of said branches, means for energizing the first of said relays in response to a call over the corresponding branch, means for locking said first relay energized in case the control trunk is busy over its other branch, means for energizing the second of said relays in the corresponding branch as soon as the control trunk becomes idle, and means responsive to the energization of the second relay for seizing the control trunk and for automatically signalling the remote operator thereover.

4. In a telephone system, a first exchange, a second exchange, a control trunk extending from a remote operator's position and terminating in two branches, the first of said branches extend-

ing to said first exchange and the second of said branches extending to said second exchange, a first and a second relay individual to each of said branches, means for energizing the first of said relays in response to a call over the corresponding branch, means for locking said first relay in energized position, means responsive to the energization of said first relay for energizing the second of said relays in the corresponding branch in case said control trunk is idle, means for unlocking said first relay in response to the operation of said second relay, means for locking said second relay in energized position, means responsive to the operation of said second relay for connecting said corresponding branch to the control trunk, and means controlled by said second relay for automatically signalling the remote operator over said control trunk.

5. In a telephone system, a first exchange, a second exchange, a control trunk extending from a remote operator's position and terminating in two branches, the first of said branches extending to said first exchange and the second of said branches extending to said second exchange, a first connecting relay for connecting the first exchange to said control trunk by way of said first branch, a second connecting relay for connecting the second exchange to said control trunk by way of said second branch, and operator controlled means controlled over said control trunk from the operator's position for selectively operating either of said connecting relays to operatively connect the control trunk to the desired exchange.

6. In a telephone system, a first exchange, a second exchange, a control trunk extending from a remote operator's position and terminating in two branches, the first of said branches extending to said first exchange and the second of said branches extending to said second exchange, means responsive to a call in either one of said exchanges for transmitting a signal over its corresponding branch, means in said branches operated in response to said transmitted signal, and means operated in response to the operation of said last means for repeating said signal to signal the remote operator over said control trunk.

7. In a telephone system, a first exchange, a second exchange, a control trunk extending from a remote operator's position and terminating in two branches, the first of said branches extending to said first exchange and the second of said branches extending to said second exchange, means responsive to a call in either one of said exchanges for transmitting a signal over its corresponding branch, means in said branches operated in response to said transmitted signal, branch connecting means operated in response to the operation of said last means in case the control trunk is idle or thereafter operated as soon as the control trunk becomes idle to connect the control trunk to the calling exchange, and means operated in response to the operation of either of said branch connecting means for repeating said signal to signal the remote operator over said control trunk.

8. In a telephone system, a first exchange, a second exchange, a control trunk extending from a remote operator's position and terminating in two branches, the first of said branches extending to said first exchange and the second of said branches extending to said second exchange, a first connecting relay for connecting the first exchange to said control trunk by way of said first

branch, a second connecting relay for connecting the second exchange to said control trunk by way of said second branch, subscriber controlled means in the first exchange for operating 5 said first connecting relay to connect the control trunk to said first exchange by way of said first branch in case the control trunk is idle, subscriber controlled means in the second exchange for operating the second connecting relay to connect the control trunk to said second exchange by way of said second branch in case the control trunk is idle, and operator controlled means controlled over said control trunk for selectively operating either of said connecting relays to oper- 10 atively connect the control trunk to the desired exchange.

9. In a telephone system, a first exchange, a second exchange, a control trunk extending from a remote operator's position and terminating in 20 two branches, the first of said branches extending to said first exchange and the second of said branches extending to said second exchange, a

first connecting relay for connecting the first ex- change to said control trunk by way of said first branch, a second connecting relay for connecting the second exchange to said control trunk by way of said second branch, subscriber controlled means in the first exchange for operating said first connecting relay to connect the control trunk to said first exchange by way of said first branch in case the control trunk is idle, subscriber controlled means in the second exchange for operating the second connecting relay to connect the control trunk to said second exchange by way of said second branch in case the control trunk is idle, means for preventing the operation of either connecting relay in case the other connecting relay is operated, and operator controlled means controlled over said control trunk for selectively operating either of said connecting relays to operatively connect the control trunk to the desired exchange. 15 20
